ARZA B. KEITH, OF NORTH BRIDGEWATER, MASSACHUSETTS.

Letters Patent No. 78,211, dated May 26, 1868.

IMPROVED MACHINE FOR CUTTING HEEL-SEATS.

The Schedule referred to in these Letters Patent and making part of the same.

TO ALL WHOM IT MAY CONCERN:

Be it known that I, ARZA B. KEITH, of North Bridgewater, in the county of Plymouth, and State of Massachusetts, have invented certain new and useful Improvements in Machines for Cutting Heel-Seats; and I do hereby declare that the following, taken in connection with the drawings which accompany and form part of this specification, is a description of my invention sufficient to enable those skilled in the art to practise it.

In boots and shoes there is inserted at the shank, between the inner and outer soles, a stiffening piece, which gives considerable convexity to the sole, extending to the rear so far that the heel is seated upon a portion of the convexity. In boots there is more need of this shank-stiffening piece than in shoes, as with a flexible shank it is difficult to remove a boot from the foot.

The object of the machine which is the subject of my invention is to cut out the concavity in the heel to fit upon the convexity caused by the filling-piece, which convexity does not extend to the rear of the heel, but only commences about midway, and then increases till, at the front or straight edge of the heel, the convexity of the shank is about at its maximum.

My invention consists in combining, with a reciprocating or vibrating gouge-like knife, means for relative adjustment between the knife and the heel-holder, so as to be able, with the same machine, to cut heel-seats to fit upon different shanks, and to accommodate different shapes and sizes of heels.

The drawing shows, in vertical longitudinal section, a machine in which my invention is embodied.

a is a bed-piece, to which is pivoted, at *b*, the cutter carrying-arm *c*, which, in making a stroke to cut, is carried downward, and is returned by any convenient means, as by a treadle and spring, for example. The cutter *d* is held in place by a side set-screw against its shank, and the thrust of the cut is taken on a set-screw, *e*, which can be adjusted as the cutter or as the cutting-block *f* is worn away.

The cutting-block is held in place against a chock, *g*, by the screw *h*, and forms the bed on which the front face of the heel rests, and on which the edge of the cutter descends.

The carriage *i* is made to slide back and forth on the bed *a*, by turning the screw *j*, so as to adjust the whole heel toward or from the traversing path of the knife-edge.

The piece *k* is pivoted to slide *i*, so that its angle may be changed by operation of screw *l* and the co-operative springs *m*, to change the angle at which knife *d* will cut the seat of the heel.

On the piece *k* is an ear, *n*, in which is a set-screw, by which the position of the heel is gauged centrally with respect to the knife.

The slide *i* being adjusted with respect to the thickness of a heel, and the piece *k* being inclined forward or back, so as to give more or less inclination to the cut, and the screw in the ear *n* being adjusted so that when the operator rests a heel on the block *f*, and against the piece *k*, the position of the heel shall be central with respect to the knife, the lever *c* is caused to vibrate, to force the knife through the material of the heel, from which a chip is gouged out to correspond to the convexity made in the sole by the shank-piece where the heel has its seat.

It is not, however, intended to dispense with the employment of the triangular rand-piece, which is worked under the edge of the heel on its outer convex surface.

I claim so combining, with a reciprocating or vibrating-knife, *d*, a heel-support, *k*, that relative adjustment may be made between the two, substantially as and for the purpose specified.

Also, pivoting the piece *k* to the slide *i*, and combining therewith means for changing the angle of *k*, substantially as and for the purpose described.

Also, in combination with the piece *k*, a side adjusting-screw, substantially as set forth.

ARZA B. KEITH.
